APPLICATOR FOR V-BELT FASTENERS

Hugh L. Coats, Wheaton, Ill., assignor to Flexible Steel Lacing Company, Chicago, Ill., a corporation of Illinois

Application October 5, 1944, Serial No. 557,329

8 Claims. (Cl. 1—50)

This invention relates to improvements in belt fastener applicators and, more specifically, to applicators for the attaching members of V belt fasteners.

In flexible or hinged types of fasteners for V belts, it is generally customary to employ two U-shaped attaching members, one attached to each end of the belt, said members having interdigitated loops at their extended ends and within which loops is disposed the hinge pin or pintle. The two parallel arms of each U-shaped member are secured to the belt end, one arm on the outer or wide face of the belt. The other arm, in the particular type of fastener with which the present invention is primarily concerned, is inserted within the body of the belt and then screws or other retainer elements inserted through the two arms and intervening belt material to hold the attaching member in place against the pulling strains.

Heretofore, considerable difficulty has been encountered in properly applying the attaching members of the type described due to the necessity of embedding one of the arms within the belt material and one object of this invention is to provide a simple, preferably manually operable device, for applying such type of attaching members to V belt ends in proper alignment and to the exact depth in the belt material and, at the same time, locate the holes in the arms in the right position to receive the securing screws or elements, the latter being guided by the applicator device.

Another object of the invention is to provide a device of the character indicated such that, where the two attaching members are complementary but different, both may be properly applied by the one device.

Other objects of the invention will more clearly appear from the description and claims herein-after following, taken in connection with the accompanying drawing.

In said drawing, Figure 1 is a top plan of an applicator embodying one form of the invention, the applicator being in the full open position with the two belt ends in position and the two dissimilar but complementary attaching members in position to be pushed into the respective belt ends. Figure 2 is a transverse vertical section corresponding to the section line 2—2 of Figure 1. Figure 3 is a longitudinal vertical section corresponding to the line 3—3 of Figure 1. And Figure 4 is a view similar to Figure 3 but showing the attaching member pushed home in the belt end and one of the securing screws in place.

In said drawing, 10 and 11 denote the two ends 55 ends by the pusher block C, the base A is pro-

of a V belt to which are to be applied the two complementary attaching members 12 and 13 respectively, it being noted that member 12 has two loops 14 whereas member 13 has three loops 14.

5 Each of the attaching members are otherwise the same, being of U-shape with parallel arms 15 and 16 as best shown in Figure 3, the ends of the arms being beveled or sharpened as indicated at 17.

The applicator proper, as shown, preferably 10 comprises, broadly, a main base or block A; a clamping or holding plate B; a slide or pusher block C; and a power applicator D.

The main base A of metal is of generally 15 rectangular shape with two parallel, laterally spaced beds or tables 18 and 19 on which the belt ends 10 and 11 are adapted to be placed and their ends gauged or stopped by gauge pins 20 and 21. Along each side of a portion of their length at the left hand end, as viewed in Figure 1, the base is 20 provided with upstanding retaining and guiding flanges 22—22 for the clamping plate B, and, for the balance of the base A with shallower flanges 122—122 that serve as guides for the pusher block C.

25 The clamping plate B is provided on its under face with inverted V shaped grooves or recesses 23—23 of such size and shape as to properly fit the belt ends to which the fasteners are to be attached. Said plate B is clamped tight on the belt 30 ends by any suitable means such as the wing nut 24 cooperable with a threaded stud 25 secured to the base A and extending vertically through an opening in the plate B as shown. On its under-side at the right hand end as viewed in Figure 1, the plate B is partially cut away or relieved at 26 35 for a distance corresponding approximately to the length of the finally embedded arm of the attaching members to allow for the swelling of the belt material that necessarily occurs when the arm is inserted and the screws also applied.

The pusher block C reciprocates toward and 40 from the clamping plate B, being guided by the flanges 122—122. On its leading face, the block C is suitably notched, as indicated at 112 and 45 113 to receive and center the loops of the respective attaching members 12 and 13. The block C may be actuated either directly by hand or by any suitable power applying means, preferably a screw D threaded in a nut section 27 formed integral with the base A, said screw having a suitable hand wheel 28 at its outer end and having swiveled connection with the pusher block C as indicated at 29. To guide the attaching members while being moved toward and into the belt 50 55 ends by the pusher block C, the base A is pro-

vided with recessed guides or grooves 30-30 of a depth corresponding to the thickness of the attaching arm, as shown.

The operation of the device so far described is as follows. The belt ends are first put in place and gauged by the stop pins 20-21, after which the clamp plate B is tightened down by the wing nut 24. The two attaching members 12 and 13 are put in place in the guide grooves 30 and the loops in the respective notches 112 and 113 whereupon, the pusher block C is actuated to push the upper arms of the attaching members into the body of the belt. In this connection, it is to be observed that the limit of movement of the pusher block C to the left is determined by engagement with the belt ends, the block C being recessed as indicated at 31-31 to clear the stop or gauge pins 20-21. By this arrangement, assurance is made that the loops of the attaching members will be left in exactly the right position with respect to the belt ends as best shown in Figure 4. Also, it is insured that the holes 32-32 of the attaching members will be brought directly in line with the corresponding screw guide holes 33-33 in the base A. When the attaching members have been properly embedded in the belt ends, the whole device is then preferably turned upside down so that the securing screws 34 may be dropped into the holes 33 and guided thereby as they are screwed home, as will be understood.

The embodiment of the invention shown provides for the simultaneous application of two differing attaching members but it is obvious that if the two attaching members of a set are alike, the pusher block C could be modified accordingly to apply both simultaneously or simply to apply one at a time.

Although there has herein been shown and described what is now considered the preferred embodiment of the invention, the same is merely illustrative and all changes and modifications are contemplated that come within the scope of the appended claims.

What is claimed is:

1. An applicator for U-shaped attaching members of a V-belt fastener, comprising: a base member; means for clamping a V-belt end to said member; a pusher block; means for slidably guiding said block to move toward the belt end in a direction parallel to the length of the belt; and means on said member and block for holding and guiding an attaching member while the latter is being pushed toward and into the belt end.
2. An applicator for U-shaped attaching members of a V belt fastener, comprising: a base member having a supporting face for a V belt end; means for gauging the end position of the belt end; means, cooperable with the base member, for clamping the belt end in gauged position; a pusher block; means for slidably guiding said block on said base member to move toward and from the gauged end of the belt in a direction parallel to the length of the belt, said block being recessed to receive the loop end of a U-shaped attaching member whereby, upon actuation of said block toward the clamped belt end, the attaching member is forced into the belt end.
3. An applicator according to claim 2 wherein the base member is provided with a guide groove for the attaching member.

4. An applicator for a U-shaped attaching member of a V belt fastener and which attaching member has openings in the arms thereof for reception of securing elements, said applicator comprising: a base member having a supporting face for a V belt end; means for gauging the end position of the belt end; means cooperable with the base member for clamping the belt end in gauged position; a pusher block slidably mounted on said base member to move toward and from the clamped end of the belt, said block, on the face adjacent the belt end, having a recess to receive and retain also in gauged position, a loop end of the U-shaped attaching member, the pusher block being limited in its movement toward the clamped belt end by engagement with the latter, said base member having guide openings therein for said securing elements so located that said openings of the attaching member are brought into alignment with said guide openings when the attaching member has been pushed into the belt end to the limit determined by engagement of the pusher block with the belt end.

5. An applicator according to claim 2 wherein power transmitting means are mounted on the base member for actuating the pusher block.

6. An applicator for a U-shaped attaching member of a V belt fastener of that type wherein an arm of the attaching member is embedded in the belt end when in operative position, said applicator comprising: a base member having a supporting face for a V belt end and means for gauging the end of the belt; a clamping plate having a V recess on the face opposite said supporting face for clamping the belt end in gauged position, said plate being relieved adjacent the extreme end of the belt whereby to permit lateral swelling of the belt end due to embedding of the attaching member; a pusher block slidably mounted and guided on said base member to reciprocate toward and from the clamped belt end, said block being recessed on the face adjacent the belt end for the reception and gauging of a loop of the attaching member, said base member having a guiding groove for the non-embedded arm of the attaching member as the latter is pushed into the belt end.

7. An applicator according to claim 6 wherein the base member is provided with guide openings leading to the supporting face for securing elements for the attaching member when the latter is pushed home.

8. An applicator for simultaneously applying two complementary but differing U-shaped attaching members of a fastener for the ends of a V belt, said applicator comprising: a base member having supporting faces for two V belt ends arranged parallel; means for gauging the end positions of the belt ends; means, cooperable with the base member, for clamping the belt ends in gauged position; a pusher block slidably mounted on said base member to move toward and from the belt ends, said block having two recesses for receiving and retaining the loop ends of the two complementary but differing attaching members; and means on the base member for guiding the attaching members to the belt ends when the pusher block is actuated toward the belt ends.
